ALOIS THOMA, OF NEW YORK, N. Y., ASSIGNOR TO HIMSELF, SAMUEL BROMBERG, AND ARTEMUS W. WILDER, OF THE SAME PLACE.

Letters Patent No. 70,045, dated October 22, 1867.

IMPROVED KILN FOR ROASTING IRON ORES.

The Schedule referred to in these Letters Patent and making part of the same.

TO ALL WHOM IT MAY CONCERN:

Be it known that I, ALOIS THOMA, of New York, in the county and State of New York, have invented a new and improved Kiln for Roasting Iron Ore; and I do hereby declare that the following is a full, clear, and exact description thereof, which will enable others skilled in the art to make and use the same, reference being had to the accompanying drawings, forming part of this specification.

Figure 1 represents a longitudinal vertical section of my invention.

Figure 2 is a vertical transverse section of the same.

Figure 3 is a horizontal sectional view of the same, the plane of section being indicated by the line $z z$, fig. 1.

Figure 4 is a horizontal sectional view of the same, the plane of section being indicated by the line $y y$, fig. 2.

Similar letters of reference indicate corresponding parts.

This invention relates to a new furnace and to a new process for roasting iron ore, said process being particularly applicable to the treatment of magnetic iron ore, which is found in large quantities throughout the United States.

The object of the invention is to reduce the expense of the process, and to so arrange the kiln and the whole process that the roasting may be done with the use of brown coal, wood, or even peat, while heretofore only the expensive anthracite coal could be used for the purpose.

The roasting of the iron ores is done by means of the gases or products of combustion discharged from the smelting-furnace, or otherwise produced. These gases are mixed with atmospheric air, and are ignited within the kiln, thereby more fully and completely roasting the ore than could be done by any process now in use. The ore is desulphurized by the application of hydrogen gas, created by the evaporation of water led through the kiln. No direct fuel is used for the roasting process. Provision is made that the supply of air, as well as of gas, can be regulated at will.

A represents a furnace, made of fire brick or other suitable material, built upon a suitable foundation. It has a base, B, made of octagonal or other suitable shape. The upper part of the furnace is made tubular, the opening being broadest in the centre, and contracting towards the upper and lower ends, as is clearly shown in figs. 1 and 2. In the lower part of the kiln is arranged around the tubular inner opening a channel, a , of octagonal or other suitable form, as shown by dotted lines in fig. 3. The same communicates by upright channels b with a series of horizontal channels, c , arranged above the channels a , and radiating from the central chamber C, as is clearly shown in figs. 1, 2, and 3. The channels c communicate directly with the chamber C and with the outside of the furnace, as shown. Above the channels c are arranged similar radial channels, d , which also communicate with the outside and with the chamber C. The bottom of the chamber C is made slanting towards two sides, as shown, to facilitate the discharge of the ore from the chamber C, (see fig. 2.) The crest of this roof-shaped bottom is formed by an iron tube, e , perforated at the sides, and extending with one end through the sides of the kiln, as in fig. 1. The ore to be roasted is placed into the chamber C, the discharge-channels f at the bottom of the same being closed by massive blocks or doors, g , as shown in fig. 2. The gases or products of combustion discharged from the smelting-furnace, and carried thence through a pipe of suitable length to the kiln, enter the channels a through the pipe h , and pass up through the channels b into the radial channels c . The channels b may be partly covered by metal plates i , to regulate the flow of the gases. A dust-receiver, j , is arranged below the channels a , and can be emptied from j' , fig. 1. The channels a are also provided with openings k , by which they communicate with the outside, said openings being rigidly closed by blocks or doors l . They are for the purpose of allowing the cleaning of the channels a . In the channels c gases are mixed with atmospheric air, entering through the outer ends of the channels c , said outer ends being wholly or partly closed by gates m , by which the quantity of air admitted is regulated. The channels c are widened the nearer they are to the chamber C, to increase the draught. The shoulder n formed in each channel c by the widening, as well as the shoulder formed in the openings b by the plates i , prevents the gas from moving towards the outer ends of the chambers c . The combined gas and air are lighted as soon as they enter the chamber C, and roasts the ore contained therein.

The roasting by this process is very equal, as the fire can be regulated with great accuracy. And the

quantity of air and gas can also be very exactly regulated to ores of different quality and composition; no parts will be burnt up, nor will any remain raw in the centre.

To liberate the ore from the sulphur and arsenic, steam is introduced to the ore while it is heated. Water is forced into the tube *e* at its outer end, and as the tube is red hot the water will therein be converted into steam. Said steam enters the chamber *C* through the holes in the pipe *e*, and comes in contact with the ore in a superheated condition. Combining with the sulphur of the ore, the steam is converted into sulphuretted hydrogen gas. The steam has also the effect to equalize and modify the heat in the kiln, thereby equalizing the roasting process. As the sulphur is now contained in the furnace in the form of *S H*, it might again be taken up by the ores, by reducing the oxidized iron of the same, and thereby freeing the hydrogen. To prevent this, the channels *d d* are arranged. Through the same atmospheric air is conducted into the chamber *C*, and burns the *S H*, converting the same into sulphurous acid, which is innoxious, as it will not combine with the iron. The desulphurizing process is thus very complete, and its value as been tested by many experiments. The channels *d* are provided with gates *o*, to regulate the flow of the air. The roasted ores are extracted through the channels *f*. For magnetic ore, it would be well to have water poured over it while it is still glowing; thereby it crumbles, and the pounding is facilitated. The ores are now ready for the reducing-furnace.

By the use of the pipe *e* the use of a boiler for creating steam is dispensed with, and the cost of the apparatus as well as of the operation is thereby greatly reduced.

Heretofore boilers were arranged outside of the kiln for creating the steam for desulphurizing purposes. By my device the heat in the kiln is utilized and equalized, and thereby improved for creating the steam for desulphurizing the ore.

I claim as new, and desire to secure by Letters Patent—

1. The arrangement of the channels *a*, *b*, and *c* within the kiln *A B*, for conducting gas and air to the ore, substantially as herein shown and described.
2. The perforated pipe *e*, when arranged in the lower part *B* of the kiln, in combination with the channels *d d*, made as set forth.
3. The process herein shown and described of roasting ore by means of gases discharged from distant fires of any kind of fuel, as described.
4. The process herein shown and described of desulphurizing the ore while roasting the same, by conducting water into the pipe *e*, whereby the use of a steam-boiler is dispensed with, and by combining the steam produced from the water with atmospheric air, as and for the purpose set forth.

ALOIS THOMA.
